SHUTTLE CHECK

Carl D. Brown, Hopedale, Mass., assignor to
Draper Corporation, Hopedale, Mass., a corpora-
tion of Maine

Application February 24, 1937, Serial No. 127,347

2 Claims. (Cl. 139—185)

The present invention relates to fly shuttle looms and, more particularly, to shuttle checking devices for such looms.

One object of the present invention is to provide in a fly shuttle loom having a shuttle box, an improved form of shuttle actuated shuttle checking device. To this end, one feature of the invention resides in a loom having a shuttle checking element supported in a shuttle box, and 10 arranged to be engaged and moved by the shuttle in a path parallel to the path of movement of the shuttle, and means associated with said element to check the shuttle.

In the illustrated embodiment of the invention, shuttle checking elements are mounted at opposite sides of the shuttle box and are arranged for longitudinal sliding movement in paths parallel to the path of movement of the shuttle. Each shuttle checking element is arranged to frictionally engage the walls of stationary guideways formed in the front box plate and the binder to resist movement of the shuttle checking elements.

With the above and other objects and features in view, the invention will now be described in connection with the accompanying drawing and pointed out in the appended claims.

In the drawing:

Fig. 1 is a plan view of a preferred embodiment of my invention showing a shuttle entering the shuttle box;

Fig. 2 is a view similar to Fig. 1, but showing the shuttle completely in the shuttle box;

Fig. 3 is a view in side elevation; and

Fig. 4 is a view in cross-section taken along the line 4—4 of Fig. 3.

In Fig. 1 there is shown the left hand end of a lay 10 which is mounted on the lay swords (not shown) for reciprocation toward and away from the front of the loom in the usual manner. A shuttle box is carried at each end of the lay but only the left hand shuttle box is illustrated herein. The shuttle box is provided with a front member 12 forming the front box plate, and a binder 14 and a lay end 16. The lay end 16 is slotted at 18 to accommodate a picker stick 20, which carries a picker 22 for engaging and picking a shuttle 24.

The front member 12, as shown in Fig. 3, is 50 comprised of a pair of spaced plates 28, 30 formed of steel, iron, or other rigid material. The lower or supporting plate 28 is provided with a pair of projecting lugs 32 having slots through which extend bolts 34 for securing the front 55 member 12 in adjusted position on the lay end

16 and parallel to the path of movement of the shuttle 24. The upper plate 30 is spaced away from the lower plate 28 by spacing blocks 36, 38 which are held in place by rivets or other suitable fastenings. The spacing block 36 is wider 5 than the upper plate 30 and its rear face carries a friction strip 40 composed of leather or other friction material. The friction strip 40 is secured to one end of the block 36 by a screw 42 and to the other end by rivets or other fastenings. The friction strip 40 is engaged by the shuttle and operates to assist in partially checking the speed of the shuttle, as will later be described.

The binder 14 is formed of lower and upper 15 spaced plates 44, 46. The plates at their outer ends are separated by a block 48, which is secured in position by rivets or other suitable fastenings. The block 48 is apertured to receive an eccentric pin 50, which acts as a pivot for the binder 14. By rotating the eccentric pin 50, the binder 14 may be moved toward or away from the picker 22 for purposes which will later be described. The other ends of the plates 44, 46 are separated by a block 52 secured to the plates 44, 46, and which is provided with a projection 54. When the binder 14 is swung rearwardly by the incoming shuttle 24, the projection 54 moves a finger 56 which is a part of the usual protector rod type of protection mechanism 30 which need not be disclosed herein. The binder 14 is normally held in the position shown in Fig. 1, by a flat spring 57 secured to the lay end 16 by screws 58.

A block 60 is secured between the plates 44, 46 by removable pins 62, 64. The block 60 has secured to its ends and to its inner face a friction covering 66 formed of leather or other suitable friction material. The incoming shuttle 24 first engages the friction surface 66 and swings the binder 14 rearwardly of the loom to move the finger 56 and thereby prevent operation of the protection mechanism. The block 60 cooperates with the block 36 to slow down the shuttle 24 as it enters the shuttle box. The binder 14, on 40 which the block 60 is mounted, swings rearwardly, as above described, to retard or check the movement of the shuttle 24 before it strikes a pair of longitudinally moving shuttle checking elements 68, 70.

Referring now to Figs. 3 and 4, which show in detail the construction of the checking element 68, it will be noted that this element moves longitudinally in a guideway formed by the top and bottom plates 28, 30 of the front box plate 12. At 55

the outer end of the guideway, there is provided a bumper 72 formed of leather or other suitable material to act as a stop for the checking element 68. This bumper 72 is secured in position by rivets and may be replaced when it becomes worn. At the other end of the guideway, a similar bumper 74 is secured in position between the top and bottom plates 28, 30. These bumpers 72, 74 absorb the shock incident to the stopping of the checking element 68 and prevent breakage of parts.

The front checking element 68, which may be formed of iron, brass, or other like material, will now be described in detail. As shown in Figs. 3 and 4, the checking element 68 is composed of a body portion 76 having an upper surface which is in sliding contact with the lower surface of the top plate 30. The body portion 76 is provided with an upstanding flange 78 engaging the inner edge of the plate 30 and the inner edge of the bottom plate 28. The front surface of the body portion is provided with a pair of depending lugs 80 which engage the front edge of the bottom plate 28. The flange 78 and the lugs 80 maintain the checking element 68 in the guideway and prevent sidewise movement thereof. Adjacent to each end of the checking element 68, there is provided a boss 82 to receive a spiral spring 84 of suitable size and strength. A flat friction plate 86, formed of steel or other suitable material, is interposed between the bottoms of the springs 84 and the top surface of the bottom plate 28, to set up frictional resistance to relative longitudinal movement between the checking element 68 and the front box plate 12, longitudinal movement of this flat friction plate 86 relatively to the checking element 68 being prevented by stop members 88 formed at each end of the checking element 68.

The rear face of the upstanding flange 78 is provided with a friction member 90 formed of leather and backed by a flat strip 92 of steel or other rigid material. The steep strip 92 and its leather facing are riveted to the rear face of the flange 78. The outer end of the friction member 90 and steel strip 92 are curved rearwardly beyond the outer end of the checking element 68. The checking element 70 in the binder 14 is constructed in the same manner as the checking element 68. The checking element 70 is provided with a body portion 94, the top surface of which bears against the lower surface of the plate 46. An upstanding flange 96 is formed as a part of the body portion 94 and engages the front edges of the plates 44, 46. The rear surface of the body portion 94 is provided with depending lugs 98 which engage the rear edge of the bottom plate 44. Each end of the checking element 70 is provided with a boss for receiving the upper ends of springs 102. Interposed between the top surface of the plate 44 and the lower ends of the springs 102, is a friction plate 104 formed of steel, brass, or other rigid material. The plate 104 is prevented from moving longitudinally relatively to the checking element 70 by means of lugs 105 formed at the ends of the element 70. The front surface of the flange 96 is provided with a friction strip 106 backed by a flat strip 108 of steel or other rigid material. This composite strip is riveted to the front face of the checking element in the same manner as the composite strip 90, 92 is riveted or secured to the

checking element 68. The outer end of the composite strip 106, 108 is curved forwardly away from the front surface of the checking element 70.

In the operation of the device, the shuttle 24, upon entering the shuttle box, engages the stationary friction element 36 on one side, and on the other side engages the friction covering 66 on the block 60. The binder 14, which carries the block 60, is swung rearwardly by the shuttle 24, but sufficient friction is set up against the movement of the shuttle 24 to retard its speed slightly. It will be noted in Fig. 1 that the front face of the checking element 70 is not parallel to the path of movement of the shuttle 24, but is so arranged that when the binder 14 has been swung rearwardly to the position shown in Fig. 2, it is substantially parallel to the path of movement of the shuttle 24. The checking element 68 is, of course, arranged in parallelism with the path of movement of the shuttle 24. Thus, when the shuttle engages the friction strips 90, 106, the checking elements 68 and 70 attached thereto move longitudinally and parallel to the path of movement of the shuttle against the friction set up between the checking elements and the walls 25 of the guideways formed in the front box plate 12 and the binder 14. The curved ends of the friction members 90, 106 engage the end of the shuttle 24, as shown in Fig. 2, and tend to hold the shuttle in position. When the shuttle 24 moves out of the shuttle box on the next pick, the checking elements 68, 70 will move with the shuttle until they reach the ends of their respective guideways. The shuttle continues its movement out of the shuttle box and the binder 14 returns to the position shown in Fig. 1.

Having thus described my invention, what I claim as new and wish to secure by Letters Patent of the United States is:—

1. In a loom, a shuttle, a lay having a shuttle box at one end thereof, a binder pivotally mounted on said shuttle box, said binder having a guideway arranged to be moved substantially into parallelism with the path of movement of the shuttle, a shuttle checking element slidably supported in the guideway in said binder and arranged, when engaged by the shuttle, to move in a path substantially parallel to the path of movement of the shuttle, a plate associated with said checking element, and springs pressing said plate against the walls of the guideway for frictionally resisting the movement of said element, thereby checking the shuttle.

2. In a loom, a shuttle, a lay having a shuttle box at one end thereof, a stationary member mounted on one side of the shuttle box and having a guideway parallel to the path of movement of the shuttle, a shuttle checking element slidably mounted in said guideway for engagement by the shuttle, a binder pivotally mounted on the other side of the shuttle box and having a guideway arranged to be moved substantially into parallelism with the path of movement of the shuttle, a cooperating shuttle checking element slidably supported in the guideway in said binder and arranged, when engaged by the shuttle, to move in a path parallel to the path of movement of the shuttle, and means associated with each of said elements for frictionally resisting movement of said checking element, thereby checking the shuttle.

CARL D. BROWN.
